Specification for Design.

Patented Mar. 28, 1916.

Application filed January 28, 1915. Serial No. 4,960. Term of patent 14 years.

To all whom it may concern:

Be it known that we, CARL A. BROWN, residing at Cleveland, in the county of Cuyahoga and State of Ohio, and FLORENCE L. GRANT, residing at Fostoria, in the county of Seneca and State of Ohio, citizens of the United States, have invented a new, original, and ornamental Design for Artificial-Light Inclosures, of which the following is a specification, reference being had to the accompanying drawing, forming a part thereof.

The figure is a view in perspective of a globe comprising our new design.

Copies of this patent may be obtained for five cents each, by addressing the "Commissioner of Patents, Washington, D. C."

We claim:

The ornamental design for an artificial light inclosure as shown.
